UNITED STATES PATENT OFFICE.

WILLIAM G. KIRCHHOFF, OF CHICAGO, ILLINOIS, ASSIGNOR TO THE INTERNATIONAL REGISTER COMPANY, OF CHICAGO, ILLINOIS, A CORPORATION OF ILLINOIS.

REMOVABLE HANDLE FOR FARE-REGISTERS.

No. 830,791.

Specification of Letters Patent.

Patented Sept. 11, 1906.

Application filed June 16, 1905. Serial No. 265,495.

To all whom it may concern:

Be it known that I, WILLIAM G. KIRCHHOFF, a citizen of the United States, residing at Chicago, in the county of Cook and State of Illinois, have invented a certain new and useful Improvement in Removable Handles for Fare-Registers, &c., of which the following is a specification.

My invention relates to removable handles for fare-registers, &c., and has for its object to provide a new and improved device of this description.

My invention is illustrated in the accompanying drawings, wherein—

15 Figure 1 is a view of a device embodying my invention. Fig. 2 is a sectional view taken on line 2 2 of Fig. 1. Fig. 3 is a view similar to Fig. 2, showing the various parts separated. Fig. 4 shows a modified construction of the gripping device.

Like letters refer to like parts throughout the several figures.

20 In the drawings I have illustrated my device as applied to a rod or shaft adapted to be rocked or rotated to perform some suitable function—as, for example, the operation of a fare-register. When the device is used to operate fare-registers, the rod extends along the length of the car and is provided with a 25 series of handles, so that the conductor may operate it from any part of the car. These handles are frequently broken, and one of the objects of my invention is to provide a handle which will be effective and which can be removed independent of the other handles and 30 without removing any of such other handles.

35 As illustrated in the drawings, the rod or shaft A is the rod or shaft adapted to be rotated. The handle proper comprises two 40 separable parts B and C. The part B is a bifurcated engaging part between the members of which the rod is received, while the part C is a handle part. The two parts are 45 removably connected together, and associated with said parts is a gripping device for gripping the rod. The two parts are preferably held together by a pin or the like C', which passes through both parts. This pin is the strain-bearing part when the handle is 50 operated. A bolt B' passes through both the parts B and C and is preferably provided at its ends with the nuts B² B³. As herein shown, the gripping device consists of the re-

movable sleeves B⁴ B⁵, which surround the bolt B' and which are received in recesses in 55 the enlarged end C² of the handle part C. The edges of these gripping-sleeves project through openings B⁶ (see Fig. 3) in the end of the handle-piece C, so as to come into contact with the rod A. The bolt B' is provided 60 with a collar B⁷, which engages the sleeve B⁴. The sleeve B⁵ is engaged by the nut B³. When it is desired to fasten the handle in position, the part B is slipped over the rod and the enlarged end of the part C is then placed 65 in position between the bifurcated ends of the part B and the pin C' fitted in position. The gripping-sleeves B⁴ and B⁵ are then placed in position and the bolt inserted and the nut B³ tightened. This forces the gripping-sleeves B⁴ and B⁵ inwardly, so that the sharp corners engage the rod A. These sleeves are preferably made of hardened steel 70 and are therefore forced into the rod so as to tightly grip it, as shown in a more or less exaggerated form in Fig. 2. It will be seen that by moving the handle part C the rod A can be rocked or rotated. It will further be seen that the strain due to the forcing of the handle part C around is transmitted to the 75 part B by the pin C' and is not taken up by the bolt B'. Said bolt may be made loose, so as to insure the strain being removed therefrom. This is desirable because of the fact that the material of the enlarged end C² between the bolt and the rod is comparatively 80 thin and is weakened by the holes B⁶, and consequently if the strain came upon the bolt it would tend to rupture this material. By providing the collar B⁷ and leaving a 85 space between said collar and the nut B³ the nut B² can be tightened so as to force the members of the bifurcated part B tightly 90 against the faces of the enlarged end C², thus reducing the shearing strain upon the pin C' 95 to a minimum.

The fit of the pin C' is such that it may be easily removed by pressing upon one end, and the nuts B² and B³ are preferably of such size as to cover up the ends or at least partially cover them up, as shown in Fig. 2, so as to prevent the pin from falling out when the parts are in position. If the handle becomes broken or for any other reason it is desirable to remove it, it is only necessary to remove 100 the nut B³ and withdraw the bolt B' and then 105

remove the pin C'. The parts B and C may then be separated, so as to be removed from the rod. When the ordinary handles containing simply an opening for the rod and 5 set-screws for binding them to the rod are used, it will be seen that if a handle is broken it becomes necessary to remove all the other handles between it and the end of the rod before the broken handle can be removed. It 10 will further be seen that because of the fact that the set-screws mutilate the rod there will be difficulty in sliding the handle past each of these mutilations. All such difficulties are obviated by this construction, as is 15 also the difficulty due to the slipping of the set-screw when the handle is operated, and a handle is produced which is easily attached to and detached from the rod.

It will be seen that one of the sleeves B⁴ or 20 B⁵ may be omitted, if desired, although the device is more symmetrical if both are used.

I have described in detail a particular construction embodying my invention, but it is 25 of course evident that the parts may be varied in many particulars and some of the parts omitted and others used with parts not herein shown without departing from the spirit of my invention, and I therefore do not wish to be limited to the particular construction and 30 arrangement illustrated.

In Fig. 4, for example, I have shown the gripping part B⁴ as integral with the bolt and the sleeve B⁵ as integral with the nut B³.

I claim—

35 1. A removable handle comprising two separable parts, one provided with members between which the device to which the handle is attached is received and projecting beyond said device, the space between said 40 members being substantially equal to the thickness of the device to which the handle is attached the end of the other part also received between said members, a removable gripping device associated with said parts and adapted 45 to grip said device, and means for connecting the parts together.

50 2. A removable handle comprising two separable parts one provided with members between which the device to which the handle is attached is received and projecting beyond said device, the end of the other part also received between said members, a bolt passing through both parts, a sleeve on said bolt adapted to engage the device when the 55 parts are in position so as to cause the device to move with the handle.

55 3. A removable handle comprising two separable parts, one provided with members between which the device to which the handle is attached is received and projecting beyond said device, the end of the other part also received between said members, a bolt passing through both parts, a sleeve on said bolt adapted to engage the device when the 65 parts are in position so as to cause the device

to move with the handle, and a strain-bearing connection between the two parts of the handle.

4. The combination with a rod of a removable handle comprising two separable parts, one provided with members between which the rod is received and which project beyond the rod, the end of the other part being the handle part and having its end also received between said members, a bolt passing through both of said parts, a sleeve on said bolt projecting into a recess in the handle part, an opening in said handle part through which the edge of the sleeve projects so as to engage said rod, and a nut on said bolt for forcing the sleeve toward the rod.

5. The combination with a rod of a removable handle comprising two separable parts, one provided with members between which the rod is received and which project beyond the rod, the end of the other part being the handle part and having its end also received between said members, a bolt passing through both of said parts, a sleeve on said bolt projecting into a recess in the handle part, an opening in said handle part through which the edge of the sleeve projects so as to engage said rod, a nut on said bolt for forcing the sleeve toward the rod, and a connecting-piece passing through both of said parts to connect them together.

6. The combination with a rod of a removable handle comprising two separable parts, one provided with members between which the rod is received and which project beyond the rod, the end of the other part being the handle part and having its end also received between said members, a bolt passing through both of said parts, a sleeve on said bolt projecting into a recess in the handle part, an opening in said handle part through which the edge of the sleeve projects so as to engage said rod, a nut on said bolt for forcing the sleeve toward the rod, and a pin loosely passing through both of said parts and adapted to be held in position by the said bolt when in place.

7. The combination with a rod of a removable handle provided with two separable parts, one having members between which the rod is received and projecting beyond the rod, the other constituting the handle part and having its end also between the said members, a bolt provided with a collar and passing through both of said parts, two sleeves on said bolt, two recesses in said handle part into which said sleeves are received and provided with openings through which the edges of the sleeves project so as to engage said rod, and a nut on each end of said bolt.

8. The combination with a rod of a removable handle provided with two separable parts, one having members between which the rod is received and projecting beyond the

rod, the other constituting the handle part and having its end also between the said members, a bolt provided with a collar and passing through both of said parts, two sleeves on said bolt, two recesses in said handle part into which said sleeves are received and provided with openings through which the edges of the sleeves project so as to engage said rod, a nut on each end of said bolt, a connecting-piece loosely passing through both of said parts, the removal of which is prevented by the nuts on said bolt when in place.

9. The combination with a rod of a removable handle comprising two separable parts, one provided with members between which

the rod is received, and which project beyond the rod, the end of the other part also received between said members, said latter part being the handle part, a bolt passing through both of said parts, a portion of the material of the handle part interposed between the bolt and said rod, said material cut away at two points, two sleeves on said bolt of such length that the edges project through said cut-away portions so as to engage said rod, the sleeves being separated by a portion of the material of the handle part surrounding said bolt.
